UNITED STATES PATENT OFFICE.

THEODOR KLEIMEIER, OF COVINGTON, KENTUCKY, ASSIGNOR OF ONE-HALF TO ALEXANDER DAVEZAC, OF SAME PLACE.

CAR-COUPING.

SPECIFICATION forming part of Letters Patent No. 556,990, dated March 24, 1896.

Application filed November 11, 1895. Serial No. 568,513. (No model.)

To all whom it may concern:

Be it known that I, THEODOR KLEIMEIER, a citizen of the United States, and a resident of the city of Covington, in the county of 5 Kenton and State of Kentucky, have invented certain new and useful Improvements in Car-Couplers, of which the following is a specification.

The several features of my invention and 10 the various advantages resulting from their use conjointly or otherwise will be apparent from the following description and claims.

In the accompanying drawings, making a 15 part of this application, and in which similar letters of reference indicate corresponding parts, Figure 1 is a top view of a car-coupler embodying my invention. Fig. 2 is a view of the said coupling after the upper portion has been removed and showing the device locked. 20 Fig. 3 is a view of the said car-coupling after the upper portion has been removed and showing the coupling device in the position the parts assume when the device is unlocked. Fig. 4 is a front elevation of the draw-head. 25 Fig. 5 is a view in elevation of that side of the hook which is toward the rear end of the draw-bar. Fig. 6 is an elevation of that side of the driver which is next to the hook. Fig. 30 7 is an end view of the free or forward end of the governor. Fig. 8 is an elevation of the front side of the locking-piece.

A indicates the draw-bar. As there is nothing novel about its construction in the present application, further description of it is unnecessary.

B indicates the shell of the draw-head. This frame has two projections, respectively marked C and D. The projection C carries 40 the hook F, pivoted at F², to the said projection. This hook consists, in general, of the latch-piece F³ and of the hook F⁴ and is pivoted between these two parts at F² to the frame B of the draw-head. The space in 45 front of the middle portion of the hook and between the hook F⁴ and latch-piece F³, I have denominated by the letter S. The hook is provided with a groove F⁵ for the insertion of a link and with a vertical hole F⁶ for the insertion of the pin to hold the link in place and thus enable this hook and its coupling to

be used in connecting cars by means of a coupling link and pin when for any reason my improved coupling is not to be used. The hook is provided with the projection or shoulder F¹², which, when the coupling is unlocked, 55 impinges against a projection C² of the draw-head, thereby preventing the hook from opening too far in the process of uncoupling the draw-head.

The free end of the latch or tailpiece F³ is flat at F⁷, and a corner of this end is cut away, thus forming a bevel F⁸. In the rear side of the lower portion of the latch is a recess F⁹. The functions of the flat end F⁷ and of the 65 beveled portion F⁸ and of the recess F⁹ will be hereinafter described.

The projection D is inwardly inclined from its forward end toward the center of the draw-head, forming an inclined bevel D², substantially as shown. The space between the projections C and D of the draw-head is indicated by the letter E.

The draw-head is provided with a passage G, running at substantially a right angle to 75 the axis of the draw-bar. In this passage is pivoted the rear end of a locking-piece H, pivoted at G² on pivot G³, and whose inner and free end H² is capable of movement in a vertical arc, of which this pivot G³ is the center. The pivot G³ is kept from withdrawal 80 by holding-screw G⁴.

When the hook F is locked, as in Figs. 1 and 2, the flat end F⁷ of the tailpiece of said hook is against the free end H² of the locking-piece H and is thereby locked. Elevation of this free end of the locking-piece lifts it up 85 away from and out of contact with the end of the latch-piece F³, and thus unlocks the hook F and leaves the latter free to swing 90 open and take the position shown in Fig. 3.

The elevation of the free end H² of the locking-piece H is accomplished by means of a rod, link, chain, or cord or any other preferred means. In the present illustrative instance the lower end of a rod I is pivoted at I² to the said free end H² of the piece H. This rod passes up through a slot B² of the draw-head. To the upper end of this rod a handle or other suitable draw-pull device is connected. Thus the operator engaged in uncoupling one car from another is enabled to 95 100

ment the free end of the latch-piece F^3 comes out from under the free end of the locking-piece H into the position shown in Fig. 1, whereupon the free end of locking-piece H falls and, engaging the free end of the latch-piece, locks it and the hook F . It will be noticed that the latch-piece F^3 when unlocked covers the flat portion of the governor at and around the pivot J^2 , the recess F^9 in the back side of the latch-piece permitting such operation.

My invention is economical of manufacture, simple in construction, easy and certain of operation and efficacious in result. Its advantages are many and obvious.

What I claim as new and of my invention, and desire to secure by Letters Patent, is—

1. A car-coupling having a hook pivoted substantially as shown, a vertically-oscillatory locking-piece H , in groove G of the draw-head, and a governor J , pivoted at J^2 to the draw-head, and a spring connected to the governor and to the draw-head in the groove G , for impelling the governor against the latch of the hook, substantially as and for the purposes specified.

2. In a car-coupling, the combination of a pivoted hook, a locking-piece for engaging the hook, a groove G in which the locking-piece acts, and a governor for propelling the latch-piece of the hook forward, when the latter is unlocked, the pivoted governor for moving the hook, and the draw-head provided with a groove L , and a spring K lying in said groove L below the governor, and in the groove G below the locking-piece, substantially as and for the purposes specified.

3. In a car-coupling, the combination of a draw-head, a coupling-hook pivoted thereto, a vertically-oscillatory locking-piece, for engaging the latch of the hook, a governor J and a spring for impelling the latch-piece of the hook, the governor having the curved flange J^7 , high at J^9 , and low at J^8 , and J^{10} , for elevating the locking-piece, substantially as and for the purposes specified.

4. In a car-coupling, the combination of a draw-head, a coupling-hook pivoted thereto, a vertically-oscillatory locking-piece, for engaging the latch of the hook, a governor J and a spring for impelling the latch-piece of the hook, the governor having the curved flange J^7 , high at J^9 , and low at J^8 and J^{10} , for ele-

vating the locking-piece, the locking-piece having the recess H^3 , on its under side, for the passage thereunder of the governor, substantially as and for the purposes specified.

5. In a car-coupler, the combination of the draw-head, a coupling-hook, a vertically-oscillating locking-piece, a pivoted governor having at the front upper edge a bevel J^6 , for acting in conjunction with the locking-piece, substantially as and for the purposes specified.

6. In a car-coupling, the combination of a draw-head, a coupling-hook, a vertically-oscillating locking-piece, having a recessed under portion H^3 , a pivoted governor having an arcal free end provided with an upper curved flange J^7 , J^8 , J^{10} , and an upper front bevel J^6 , substantially as and for the purposes specified.

7. In a draw-head, having a pivoted coupling-hook, a locking-piece, and a pivoted governor J impelled outward by a spring, the governor being cut down at and in the vicinity of the pivot, and the hook having an undercut rear recess F^9 , for overlapping the pivotal portion of the governor when the hook is locked, substantially as and for the purposes specified.

8. In a draw-head, the pivoted coupling-hook having the oscillating latch-piece F^3 , the rear upper edge of whose free end has a bevel F^6 and a vertically-oscillating locking-piece H^3 having the bevel H^5 projecting out from the front lower edge of the latter, and on a level with the bevel F^6 , and a pivoted governor adapted to receive the projection H^4 , H^5 , substantially as and for the purposes specified.

9. In a draw-head, with shoulder-stop C , the pivoted coupling-hook having the stop F^7 , the hook part F^4 and latch-piece F^3 , and the oscillating locking-piece H , and pivoted governor adapted when the locking-piece is out of engagement with the hook to press forward the hook-latch F^3 and pass under the locking-piece, and being checked by the stops aforesaid, to remain under and uphold the locking-piece, substantially as and for the purposes specified.

THEODOR KLEIMEIER.
